CLAIM

The ornamental design for a toy building element, as shown and described.

DESCRIPTION

It is intended that the toy building element of the present invention be used in a set of toy building blocks that are capable of being interconnected in a releasable engagement. FIG. 1 is a top perspective view of the toy building element. FIG. 2 is a side view of the embodiment of the toy building element shown in FIG. 1. All four sides of this embodiment are identical.

FIG. 3 is a top view of the embodiment of the toy building element shown in FIG. 1; and,

FIG. 4 is a bottom view of the embodiment of the toy building element shown in FIG. 1.
